UNITED STATES PATENT OFFICE.

JULIUS LIBROWICZ, OF NEW YORK, N. Y.

DESIGN FOR A BOTTLE STOPPER OR TOP.

SPECIFICATION forming part of Design No. 22,168, dated January 31, 1893.

Application filed November 3, 1892. Serial No. 450,903. Term of patent 7 years.

To all whom it may concern:

Be it known that I, JULIUS LIBROWICZ, a citizen of the United States, residing at New York, county of New York, and State of New 5 York, have invented and produced a new and original Design for Bottle Stoppers or Tops, of which the following is a specification.

Reference is had to the accompanying drawings, forming part of this specification, in 5 which—

Figure 1 is a front elevation, showing the bust and supporting inverted cup or base; and Fig. 2, a sectional elevation of the said cup or base taken on the line $x x$, Fig. 1.

5 The stopper or top comprises two parts, to wit: a bust 1 and a cup shaped base 2. The bust is that of a figure appareled in military clothes, having epaulets on the shoulders; a

high collar to the coat which extends up and under the beard which covers the lower face, 20 the hair of the head being parted on the left side. The case is cylindrical, cup shaped, and hollow as shown at 3, the lower portion of which is provided with a concentric rib 4. The exterior of the base is provided with a 25 series of concentric grooves 5.

I claim:

The design for a bottle stopper, or top, herein shown and described.

Signed at the city, county, and State of New 30 York this 2d day of November, 1892.

JULIUS LIBROWICZ.
